UNITED STATES PATENT OFFICE.

CHARLES E. H. LLOYD, OF LOS ANGELES, CALIFORNIA.

SPRAYING-NOZZLE FOR INTERNAL-COMBUSTION ENGINES.

1,301,719.

Specification of Letters Patent. Patented Apr. 22, 1919.

Application filed April 8, 1918. Serial No. 227,293.

To all whom it may concern:

Be it known that I, CHARLES E. H. LLOYD, a citizen of the United States, residing at Los Angeles, in the county of Los Angeles and State of California, have invented new and useful Improvements in Spraying-Nozzles for Internal-Combustion Engines, of which the following is a specification.

My invention relates to a device for feeding or spraying oil under pressure and discharging the same into the ignition chamber of an internal combustion engine, and particularly to a device adapted to feed the heavier distillates of petroleum.

15 A main object of my invention is to provide an atomizing discharge nozzle which may be readily regulated to suit the pressure at which the oil is delivered thereto.

Another object of my invention is to effect 20 a substantially perfect atomization and distribution of hydro-carbon oils at each injection, whereby to effect a more perfect and instantaneous combustion, without the usual carbonization within the ignition chamber.

25 A still further object is to provide a simple oil spraying device for an outlet orifice controlled by a spring closure, in which the tension of the spring controlling the closure may be increased or diminished according to 30 the oil pressure delivered to the injector.

A further object is to provide a device in which the outlet orifice, which is normally closed, will be instantly opened on the introduction of oil under pressure.

35 I accomplish the above objects by means of the device herein described and illustrated in the following drawings, in which:

Figure 1 is a central longitudinal section through my complete device showing it attached to a wall of the ignition chamber.

Fig. 2 is a transverse section through the device taken on line 2—2 of Fig. 1.

The invention illustrated in the drawings preferably consists of an elongated body 45 member 5 having a central bore 6 of uniform diameter extending throughout its entire length. The extreme outer end of member 5 is of reduced external diameter, and the end of bore 6 is threaded for the reception of a 50 hollow nozzle cap 7 provided with a centrally disposed outlet orifice 8 of minute diameter, a gasket 9 being interposed between cap 7 and the outer end of member 5 to insure a liquid tight joint. Member 5 directly back of its reduced portion is externally threaded as at 10 for securing said

member in rigid engagement with the threaded opening formed in the wall of the ignition chamber of the engine. The end of member 5 opposite its nozzle end is of an 60 enlarged diameter as at 12, and is provided with radial bore 13 for the reception of an oil inlet pipe (not shown). The end of member 5 opposite its nozzle is flanged as at 15 for the reception of a hollow flanged cap 65 16 which is secured to flange 15 of member 5 by means of cap screws 17 or other suitable securing means.

Slidably mounted in bore 6 of member 5 is a closure rod 18, the outer end thereof being 70 of reduced diameter so as to loosely fit the bore of the nozzle cap 7 to permit of a flow of oil to the nozzle orifice, the extreme end of said rod being provided with a ball 20 adapted to normally close orifice 8 of the 75 nozzle.

Mounted on the reduced outer end of closure rod 18, and interposed between the inner end of nozzle cap 7 and the shoulder 21 formed by the reduced end of rod 18, is a 80 coiled spring 22 adapted to force rod 18 rearwardly and unseat the ball valve 8 on the entrance of oil under pressure through inlet bore 13, as will be more particularly explained hereinafter. The rear portion of 85 closure rod 18 back of the reduced outer portion is provided with a plurality of longitudinally disposed semi-circular oil inlet grooves 23, through which oil is introduced to the outer end of member 5. The rear end 90 of rod 18 is partially spherical in form and contacts with a circular metallic diaphragm 24 clamped between the flange 15 of member 5 and the flange cap 16, the diaphragm preventing the entrance of oil into the recess 95 formed in the flange cap 16.

The flanged end of member 5 is provided with an annular recess 25, and the flanged end of nozzle cap 16 is also recessed as at 26, the two recesses 25 and 26 permitting a 100 movement of the diaphragm 24 when rod 18 is moved rearwardly to unseat the ball from its orifice.

Mounted in recess 27 of flange cap 16 is a 105 coil spring 28, the tension of said spring being normally greater than the tension of spring 22 mounted on the forward end of rod 18, mounted in the ends of the spring 22 are buttons 29 and 30, button 29 bearing against the diaphragm 24 while the head of 110 button 30 contacts with the end of a set screw 31. By means of this set screw the

tension on spring 28 may be increased or diminished according to the pressure at which the oil is admitted through inlet bore 13.

- 5 The operation of my improved nozzle will be clearly apparent from the following description: The nozzle is first screwed into the wall of the ignition chamber of the engine and oil introduced under a suitable pressure, 10 the oil being forced intermittently into the nozzle. As the oil enters the nozzle under pressure, it fills chamber or recess 25 at the outer end of member 5 so as to force the diaphragm and the ring 28 rearwardly, this permitting 15 spring 22 to force rod 18 rearwardly and unseat the ball from the outlet orifice. The moment the ball is unseated the oil rushes through the outlet orifice under pressure and sprays or atomizes the oil in a mist-like spray. As soon as the pressure is relieved, 20 spring 28 will overcome the action of spring 22 and again seat the ball until another charge of oil is introduced.

By means of set screw 31 I am enabled to 25 control the tension of the spring according to the pressure of the oil delivered to the nozzle.

What I claim is:

1. In a spraying nozzle, a hollow nozzle member having a fluid inlet leading thereto and a fluid outlet leading therefrom, a valve mounted in said member, a spring bearing against said valve to normally close said fluid outlet, and a spring of less tension than the first named spring to actuate said valve to open said outlet when the tension of the first named spring is overcome, the tension of said spring being overcome by the introduction of a fluid under pressure to said nozzle member.
2. In a spraying nozzle, a hollow nozzle member having a fluid inlet leading thereto and a fluid outlet leading therefrom, a reciprocating valve mounted in said member, 45 resilient means cooperating with said valve to seat the same in the fluid outlet opening, and resilient means to retract said valve to open said outlet when said first named resilient means is rendered inoperative.
3. An oil spraying nozzle, comprising a nozzle member provided with a centrally disposed bore and having a fluid inlet leading to said bore and a fluid outlet leading therefrom, a valve means for controlling said fluid outlet, resilient means bearing against said valve means to normally maintain the fluid outlet in a closed condition, and re-

silient means to actuate said valve means to open said outlet on the introduction to said nozzle member of a fluid under pressure. 60

4. In a spraying nozzle, a nozzle member having a centrally disposed bore therein terminating at the outer end in an oil outlet orifice, said nozzle adapted to be secured in the wall of an ignition chamber of an engine, said member being further provided with an oil inlet opening in its bore, a recessed cap secured to the inner end of said nozzle member, a metallic diaphragm secured between the nozzle member and said recessed 65 cap, a closure rod having oil ways communicating with the outlet end of said nozzle member mounted in the bore of said nozzle member, a resilient means acting on said rod to unseat the same at intervals, a resilient means mounted in the recessed cap member and normally bearing against the closure rod to close the outlet orifice in the nozzle member, and means to increase or diminish the tension of said last named resilient 70 means.

5. In a spraying nozzle, a hollow nozzle member having a fluid inlet leading thereto and a fluid outlet leading therefrom, a valve closure rod having a plurality of longitudinal 85 grooves therein and a reduced outer portion mounted in said nozzle member, said grooves extending from the larger end of said rod to the reduced end thereof, an interior shoulder formed within said nozzle 90 member adjacent the end thereof, a coil spring mounted on the reduced end of said rod between the shoulder formed within the outer end of the nozzle member and the shoulder formed by the reduced end of the 95 rod, the outer end of said rod closing said outlet, a metallic diaphragm mounted on said nozzle member on the inner end thereof and bearing against the outer end of said rod, a spring of greater tension than the spring 10 mounted on the rod bearing against said diaphragm to force said rod forwardly and close said outlet opening, and means to increase or diminish the tension of said last named spring, the said first named spring 11 adapted to unseat the outlet closure rod on the admission of a fluid under pressure to said nozzle member, said fluid overcoming the tension of the last named spring.

In witness that I claim the foregoing I 11 have hereunto subscribed my name this 25th day of March, 1918.

CHAS. E. H. LLOYD.
